UNITED STATES PATENT OFFICE.

VIKTOR BUNYEVÁCZ, OF BUDAPEST, HUNGARY, ASSIGNEE, BY MESNE ASSIGNMENTS,
OF ONE-HALF TO ALEXANDER ROMAN, OF NEW YORK, N. Y.

SNAP SWITCH.

Application filed February 9, 1922. Serial No. 535,283.

To all whom it may concern:

Be it known that I, VIKTOR BUNYEVÁCZ, a citizen of Hungary, and resident of Budapest, Hungary, have invented certain new and useful Improvements in Snap Switches, of which the following is a specification.

The present invention relates to improvements in electric switches, and more particularly to snap-switches.

10 The main object of the invention is to produce a snap-switch which is simple in construction, efficient in operation, durable in use, and the elements of which are so constructed and arranged that they are not subjected to undue jars and wear in use.

15 Another object of the invention is to so construct the switch that its contact making shiftable element is effectively prevented from resting in any halfway position and 20 thus from establishing an arc.

With these and other objects in view, which will more fully appear as the nature of the invention is better understood, the same consists in the combination, arrangement and construction of parts hereinafter described, pointed out in the appended claims and illustrated in the accompanying drawings, it being understood that many changes may be made in the size and proportion of the several parts and details of construction within the scope of the appended claims, without departing from the spirit or sacrificing any of the advantages of the invention.

30 Two of the many possible embodiments of the invention are illustrated in the accompanying drawings, in which:—

Figure 1 is a plan view of a switch constructed in accordance with the present invention, its cover being removed to show the interior construction; Fig. 2 is a section taken on line 2—2 of Fig. 1, with the cover in place; Fig. 3 is a view similar to the one shown in Fig. 1 of a modification of the invention; and Fig. 4 is an elevation of one of the stationary contact points employed in the device shown in Fig. 3.

Referring now first to Figs. 1 and 2 of the drawings, the numeral 10 indicates a casing, 40 provided with a cover 11. Both the casing and cover are, preferably, made of insulating material and may be of any suitable configuration. In the case illustrated, the cover is cylindrical and provided upon diametrically opposite portions of its cylindrical wall

with apertures 12, through each of which projects a push button 13, said buttons being either made integral with or attached to a bar 14, that is centrally provided with a transverse slot 15. Through this slot extends a rock-lever 16, pivoted at 17 to a lug 18. This lug is made integral with one of the stationary contact points, denoted by the numeral 19, said contact point being held, for instance, by a screw 20 upon the bottom 21 of the casing. This contact point is arranged at one side of the lever, the other stationary contact point, denoted by the numeral 22, being disposed at the other side of said lever. The contact point 22 is made in the form of a spring, for a purpose hereinafter to be described.

The rock-lever is provided adjacent the fulcrum 17 with three wedge-shaped teeth 23, adapted to co-operate with a wedge-shaped projection 24 on a blade spring 25, the latter being attached in any suitable manner to the bottom of the casing 10.

The operation of this device is as follows: When the elements are in the positions shown in full lines in Figs. 1 and 2 of the drawings, the projection 24 on the blade spring is seated between the middle tooth and the right-hand side tooth on the rock-lever, in which position the latter contacts 80 with the stationary contact point 22, establishing thus a connection between the two stationary contact points of the switch. In order to break the circuit, the bar 14 is shifted in the direction of the arrow shown in Fig. 1 of the drawings, whereby first the middle tooth on the rock-lever forces the projection 24 out of the gap between said two teeth and thereby places the blade spring under tension, the lug 24 on the latter jumping into the gap between the middle tooth and the left-hand side tooth on the rock-lever, as soon as the latter has passed its middle position. The rock-lever then occupies the position shown in dotted lines in Fig. 1 of the drawings, in which the circuit is broken. Attention is called to the fact that the spring of the stationary contact point follows the rock-lever until the latter reaches its middle position, the contact being 95 then suddenly interrupted, whereby the formation of an arc is effectively prevented.

It is to be observed that the outer teeth on the rock-lever constitutes stops, which co-operate with the wedge-shaped projection 24 110

on the blade-spring, the latter preventing a sudden jar as the rock-lever moves from one of its extreme positions to the other one, so that breakage of the lever cannot occur.

5 The modification of the invention as illustrated in Figs. 3 and 4 of the drawings differs from the one above described, in that it is made in the form of a knife-switch, the rock-lever 16 constituting the knife, which 10 co-operates with two stationary contact points 26, each of which is made in the form of a spring. These springs are disposed below the fulcrum 17 of the rock-lever. The current flows in this instance through a short 15 part only of the rock-lever, as clearly appears from Fig. 3 of the drawings.

What I claim is:—

1. A snap-switch comprising a base, a bar 20 movable on said base in the direction of its longitudinal axis provided with a transverse slot, two stationary contact points on said base, a rock-lever pivoted to said base extending through said slot and adapted to

bridge the gap between said contact points, three wedge-shaped teeth on said rock-lever, 25 and a blade spring on said base provided with a wedge-shaped projection adapted to enter the notches between the teeth on said lever, said spring being placed under tension when its projection is unseated from one of 30 said notches as said lever is by the movement of said bar brought into middle position, whereby said projection is caused to snap into the other notch as soon as said lever has passed its middle position. 35

2. In a snap-switch according to claim 1, one of said stationary contact points being made in the form of a spring following said lever to its middle position, the contact between said spring and lever being interrupted when said lever passes its middle position. 40

Signed at Budapest, Hungary, this 6th day of Dec., A. D. 1921.

VIKTOR BUNYEVÁCZ.
